(57) **CLAIM**

The ornamental design for a biplanar single handed x-ray apparatus, as shown and described.

DESCRIPTION

FIG. 1 is a top, front and right side perspective view of a biplanar single handed x-ray apparatus;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

In the drawing views, the broken lines are included for the purpose of illustrating portions of the biplanar single handed x-ray apparatus that form no part of the claimed design.
